UNITED STATES PATENT OFFICE.

ARTHUR J. BLACKWOOD, OF CARRBORO, NORTH CAROLINA.

ADJUSTABLE ROLLER-HOLDER.

1,130,880.

Specification of Letters Patent.

Patented Mar. 9, 1915.

Application filed July 20, 1914. Serial No. 852,053.

To all whom it may concern:

Be it known that I, ARTHUR J. BLACKWOOD, a citizen of the United States, residing at Carrboro, in the county of Orange and State of North Carolina, have invented a new and useful Adjustable Roller-Holder; and I do hereby declare the following to be a full, clear, and exact description of the invention, such as will enable others skilled in the art to which it appertains to make and use the same.

This invention relates to roll stands for spinning machines, and particularly a stand which may be used on jack frames, fly frames, intermediates, slubbers, drawer frames, etc.

The present form of stand is provided with a fixed roll support or bearing in the forward portion thereof, and two movable roll supports for bearings, each being individually adjustable and individually removable without interference with the remaining bearing. In other words, one of the movable bearings may remain perfectly intact while the other movable bearings may be removed and vice versa.

One of the features of the invention is the provision of swiveled screw members for adjusting each one of the removable bearings, including means for locking the screw members when being adjusted. Said screw members are relieved of the necessity of removing the same, when detaching one of the removable bearings.

In practical fields the details of construction may necessitate alterations, falling within the scope of what is claimed.

The invention comprises further features and combination of parts, as hereinafter set forth, shown in the drawings, and claimed.

In the drawings:—Figure 1 is a view in perspective of the improved roll stand constructed in accordance with the invention. Fig. 2 is a longitudinal sectional view, Fig. 3 is a transverse sectional view, on line 3—3 of Fig. 2. Fig. 4 is a detail view of one of the roll supports or bearings and its attending part for holding the bearing mounted on the stand. Fig. 5 is a fragmentary top view.

Referring to the drawings 1 designates the standard, upon the upper end of which a head 2 is formed, which is provided with a bearing 3 for the reception of a spindle (not shown) of a fixed roll (not shown). This bearing has a copper seat 4 dove-tailed

or otherwise fixed in said head. Projecting rearwardly of the head 2 is a bar 5 having a slot 6 forming a guide for the tongue 7 and 8 of the angular members 9 and 10. The tongue 7 of the member 9 is so arranged, that is, offset forwardly of the face 11 of the member 9, so that the bearing member 12 may be adjusted flat against the bearing member 13. In other words, so that the faces 14 and 15 of said bearing members will contact. The bar 5 is provided with guides 16 adjacent the slot, and in which guides the tongues 17 and 18 of the bearing members 12 and 13 engage, so as to guide the bearing members 12 and 13 in their movements. The members 12 and 13 are provided with bearing seats 19 and 20 for the reception of the spindles (not shown) of the roll (not shown) of a spinning machine. A downwardly projecting member 21 is secured to the end 22 of the bar 5 by means of a screw 23. The upper portion of the face of the downwardly projecting member 21 is constructed with a lug 24 to engage between the shoulders 25 of the upper portion of the bar 5, to prevent twisting or displacement of the member 21. Threaded through the member 21 are two screws 26 and 27. One end of the screw 26 is swivelly connected as shown at 28 and 29 to the angular member 10, the screw 27 has one end swivelly connected at 30 and 31 to the angular member 9. By adjusting either one of the screws 26 or 27 the angular members 9 and 10 may be moved longitudinally of the bar 5 and with them the bearing members 12 and 13 are movable. After adjusting the screws 26 and 27, they may be locked in adjusted positions by the lock nuts 32. Passing upwardly through the angular members 9 and 10, and through their tongues are screw bolts 33 and 34, which also pass into and threaded to the bearing thereby firmly holding the bearing members 12 and 13 upon the bar 5 so as to slide forwardly and rearwardly, whereby the rolls may be adjusted in positions desired. The swiveled connections between said screws and the angular members are detachable.

The invention having been set forth, what is claimed as new and useful is:—

1. A roll stand for spinning machines having a standard, a rearwardly extending extension bar upon its upper portion provided with a longitudinal slot and terminating at its rear end in a downwardly extend-

ing portion, a pair of roller bearing members mounted upon the bar to slide thereon, a pair of angular members carried by the bearing members, and means mounted in said downwardly extending portion provided with swiveled connections with said angular members, whereby the bearing members may be adjusted individually.

2. A roll stand for spinning machines having a standard, a rearwardly protruding extension bar upon its upper end provided with a longitudinal slot and adjoining guides, a pair of roller bearing members having tongues engaging said guides, a pair of angular members below the bar and provided with tongues extending through the slots, means for securing the angular members and the bearing members together, said means passing through the tongues of the angular members and into the bearing members and being removable whereby the bear-

ing members and angular members may be disconnected, said extension bar at its rear end terminating in a detachably connected downwardly extending portion, means to prevent said portion from twisting or displacement, screws threaded through the downwardly extending portion one above the other, each screw having a detachable swiveled connection with each angular member, means for holding each screw in adjusted positions, said screws acting to individually adjust each angular member and its attending bearing member.

In testimony whereof I have signed my name to this specification in the presence of two subscribing witnesses.

ARTHUR J. BLACKWOOD.
